FUZE

Lyle M. Cooper, Rahway, N. J., assignor to the
United States of America as represented by the
Secretary of War

Application November 7, 1944, Serial No. 562,370

3 Claims. (Cl. 102—76)

1

The invention described herein may be manufactured and used by or for the Government, for governmental purposes, without the payment to me of any royalty thereon.

This invention relates to a combination percussive and time fuze or firing mechanism particularly adapted for use in tail ejection type bombs released from aircraft in clusters.

Tail ejection incendiary bombs were given greater capabilities and became standardized when equipped with fuzes made in accordance with the present invention. The bombs are made up of two principal assemblies, the fuze and the case. The case serves as a container for an incendiary or chemical agent, an ejection charge, and the fuze. The fuze fitted into the case is the means for transforming energy of impact into a controlled ignition for firing the ejection charge.

Among others, objects of the invention are to provide a fuze sufficiently compact to increase the loading efficiency of the bomb, simple for safe handling, easy assembly and manufacture with a minimum of scarce materials, sealed for water-proofness, and constructed for dependable functioning even when the bomb slants at an angle from the vertical on impact with surfaces of various degrees of hardness.

In a preferred form the fuze of the present invention comprises a die cast base formed to hold a primer cap, a weighted striker arm or lever pivotally hinged to the base in such a position that the striker swings through a small arc (less than 45°) in functioning, and a torsion spring for holding the striker arm normally away from the primer cap. This mechanism is housed within a cylindrical metal shell, such as a steel tubing, secured to the base. The base has a longitudinal bore for insertion of a suitable time delay powder train element, such as a lead spitter fuse, leading from the bottom of the primer cap to the rear end of the base, to which is attached a booster or first fire charge in a cellulose nitrate plastic cup. The head of the base is provided with an aperture for insertion of a safety plunger generally in a central position and disposed in relation to the mechanism so that the plunger in an unarmed position prevents the striker from accidental movement in the direction of the primer cap. The foregoing described elements may be assembled into a compact unit with suitable sealing compounds to make the unit practically waterproof.

Practical embodiments of the fuze will be 55 or die cast aluminum base alloy, has parallel

2

described with reference to the accompanying drawings, wherein:

Figure 1 shows a longitudinal cross-sectional view of a fuze unit assembly in one form;

Fig. 2 shows a plan of the fuze base illustrated in Fig. 1;

Fig. 3 shows an end view of the fuze base in elevation;

Fig. 4 shows a longitudinal cross-sectional view 10 of the safety plunger assembly enlarged;

Fig. 5 shows a bottom plan view of the striker arm;

Fig. 6 shows a side view of an all-ways modification of the fuze unit assembly with a part 15 broken away and its safety plunger in an armed position;

Fig. 7 shows a longitudinal cross-sectional view of the all-ways fuze illustrated in Fig. 6 rotated through an angle of 90° about its longitudinal axis and with its safety plunger in an unarmed position;

Fig. 8 shows a cross-sectional view of the all-ways fuze taken along line 8—8 in Fig. 6.

Referring to the drawings, and particularly to 25 Figs. 1 to 5, a cylindrical shell 1 of brass, steel tubing or similar tough metal construction serves as a relatively thin-walled protective container for the fuze mechanism. The wall of shell 1 is attached to the base 2 by engagement of a small bead protrusion 3 from the base into a corresponding depression 4 in the shell 1.

The base 2 is, in general, cylindrical in outline. At the circular head of the base are small recesses 5 for receiving a spanner wrench on screwing the 35 fuze into position. An aperture 6 in the head of the fuze base holds the safety plunger assembly 7. A well 8 perpendicular to the longitudinal axis of the fuze serves as a recess for a primer cap 9.

A passageway 10 leads from the bottom of the primer cap 9 in well 8 to the circular rear end 40 of the base for holding delay fuse 11 which leads into a plastic cup 12 containing a booster charge, e.g., about 1 g. of black powder. The plastic cup 12 may be made of cellulose nitrate plastic or

similar ignitable and waterproof plastic material. Adjoining the rear end of the fuze base 2 and integral therewith are two lobes 13, both projecting parallel to a vertical plane through the long axis of the fuze and having aligned drilled 45 holes 14 for holding a hinge pin 15. Small vent holes 16 are drilled in the base transversely to the long axis of the fuze with openings at the bottom of well 8.

A striker 17, preferably made of stamped steel 50 or die cast aluminum base alloy, has parallel

ears 18 pierced by aligned drill holes 19 through which the hinge pin 15 is passed for holding the striker pivotally attached to the fuze base 2. At the free swinging end, the striker arm is weighted and carries a centrally disposed firing pin 20. In the assembled fuze the striker arm makes a small acute angle, with the longitudinal axis of the fuze, and the point of the firing pin 20 is held a short distance from the top of the primer cap 9 by the pressure of a torsion spring 21 looped around the hinge pin 15 with one end bearing against the fuze base 2 and the other end bearing against the striker arm 17, with shell 1 restricting further movement away. Small grooves 22 and 23 in the striker arm 17 and base 15 respectively, keep the ends of spring 21 from slipping sidewise.

The torsion spring 21 may be made of music wire about 0.04" in diameter looped about 2 1/4 times around the hinge pin. Variations may be made in the diameter and number of loops to adjust the degree of restraining action. In general, it is desirable that the restraining action by the spring be sufficient to prevent contact of the striker firing pin 20 with the primer when a bomb containing the fuze impacts in falling a distance of about 2 to 5 ft. onto a concrete floor, but definitely functions when dropped about 9 ft. Accordingly, the fuze may be made more or less sensitive depending upon the degree of safety desired in handling and conditions under which the bomb is desired to operate.

The safety plunger assembly 7 is of a type which has been manufactured on a large scale for use in standardized thermit incendiary bombs, but some modification is made desirable by the relatively small travel of the striker in the fuze of the present invention. The safety plunger consists of a thin-walled sleeve 24 made of brass, gilding metal, or the like, for housing a coiled spring 25 under compression and the stem 26 of a plunger pin, the plunger pin having a flange 27 which bears against one end of spring 25. In the armed position, the plunger pin has a button end 28 projecting outside the shell or sleeve 24; and in an unarmed position, the plunger pin is pressed inwardly against the spring so that the narrow stem end 26 of the plunger pin opposite the button end 28 projects into the fuze underneath the striker 17 to prevent movement thereof. By inserting a thin washer 39, fitted closely around stem 26 between the compression spring 25 and the inner end of the brass sleeve 24, the hole diameter at this end of the brass sleeve is reduced and thereby a better control of the plunger movement is obtained.

A satisfactory procedure for assembling the fuze is as follows:

(1) Press the primer cap 9 into the well 8 of the fuze base 2;

(2) Insert the safety plunger assembly 7 into the recess 6 in the fuze base 2, having the plunger generously coated with a suitable water resistant grease, e. g., a lithium base grease to keep out moisture;

(3) Assemble the striker 17, hinge pin 15, and torsion spring 21 to the fuze base 2;

(4) Insert the spitter fuse 11 in the passage-way 10 of the fuze base 2 applying a quick drying cement, e. g., Pettman cement, to hold it in place, and at the ends of the spitter fuse apply a quick match paste of black meal powder mixed with acetone and cellulose nitrate.

(5) Insert the fuze base thus assembled into the cylinder 1 until the bead 3 on the base 2

4

springs into the depression 4 at the head end of cylinder 1.

(6) Press the first fire charge cup 12 into the rear end of cylinder 1.

The completed fuze unit is then ready to be secured into a bomb body preferably by luting the threads 29 at the head of the base 2 with a suitable luting compound, such as white lead-in-oil or Pettman cement and finally having adequate water resistant grease on the safety plunger.

The fuze thus assembled should be capable of firing in a bomb after the bomb is immersed in cold water at 10° F. for 15 minutes.

In operation, when a bomb containing a fuze unit like that described becomes separated from a bomb cluster dropped from aircraft, the plunger pin being no longer pressed inwardly by an adjacent bomb body in a cluster, becomes retracted outwardly by spring 25 to thus arm the fuze. The bomb drops in a generally vertical position so that the long axis of the fuze is more or less horizontal to the ground. Upon adequate impact of the bomb on a target surface, the inertia in the weighted portion of the striker arm 17 forces the striker 17 to overcome the restraint of the torsion spring 21 and swing downwardly in the direction of the primer cap 9. The firing pin 20 on being driven into the charge of cap 9 ignites the primer material, which in turn ignites the underlying end of the spitter fuse 11. The spitter fuse gradually burns to its opposite end in a period of about 1 to 5 seconds and then ignites the first fire charge in the cup 12, giving a desired delay action which permits the bomb to penetrate a target and to fall to rest on its side before the first fire charge detonates a propellant charge disposed adjacent to the fuze unit.

Designed in accordance with the same principles that apply to the fuze illustrated in Fig. 1, but with certain modifications, an all-ways fuze which is more responsive to impact in all positions is obtained for use in incendiary bombs, grenades and other munitions. A description of the all-ways fuze is presented with reference particularly to Figs. 6, 7, and 8.

The all-ways fuze comprises two L-shaped striker levers pivoted at their corners on hinge pins 15. Each of the L-shaped levers has a short arm 17 carrying a firing pin 20 and each has a longer arm 18. The L-shaped striker levers are disposed generally in parallel positions. Any rotational movement of the longer arms 18 towards the center of the fuze serves to drive the firing pin 20 of the integrally moved short arm 17 into a primer cap 9 fixed in the fuze base 2, thereby causing firing of the primer. Movement of either of the longer arms 18 toward the center of the fuze is opposed by a spring 21 which tends to keep the longer arms 18 in a position substantially perpendicular to the base and parallel to the long axis of the fuse. The longer arms 18 are linked at about their mid-points by a taut but flexible wire or chain 31 to a relatively heavy weight 32. Movement of this weight 32 in any direction tends to move one or both of the long arms 18 toward the center of the fuse with sufficient force to overcome the restraint of spring 21, thereby rotating either or both striker levers on their pivots at hinges 15 so that the firing pins 20 on the short striker arms 17 are forced in the direction of their underlying primer caps 9. When a munition carrying the fuze received adequate impact, the momentum or inertia of the weight 32 forces it from its normal position and

one or both caps 9 are fired through the rotational movement of one or both of the striker levers with the restraining pressure of spring 21 overcome.

The previously mentioned, base 2, to which the L-shaped levers are hinged in projections 13 having aligned hinge pin bores 14, is provided with two primer caps 9. Each of the primer caps 9 is aligned under each of the firing pins 20 attached near the ends of each of the shorter arms 17 of the striker levers. The primer cap wells and a vent-hole 16 lead into an adjoining chamber, at the opposite end of which there is a central bore in externally threaded plug 18 containing a pressed powder core 11 formed of a material, which is ignited when either one or both primers 9 are fired and then burns in an approximately determined time delay period of about one or a few seconds. At the final burning end of this delay element, the base 2 has an attached plastic cup 12 filled with a booster or first fire charge of black powder. This booster charge can detonate the main charge in a bomb, grenade, or other munition in which the fuze is used. The entire fuze is preferably assembled into a tube or hollow cylinder 1 which is constructed of a tough metal, such as steel or brass, to which the base 2 and the head having threaded end 29 are connected by means of small screws 33, or the like.

Likewise, in a manner similar to that employed in the fuze illustrated by Fig. 1, the all-ways fuze shown in Figs. 6, 7, and 8 may be provided with a simple safety means which is capable of keeping the fuze unarmed through the application of an external pressure in a cluster. This safety mechanism is one of the same general design as the safety plunger assembly shown in Fig. 4 except for the attachment of a metal disk 34 to the end of the plunger stem 26 opposite the button end 28. The extreme ends of the long arms 18 of the striker levers are bent over toward each other so that they terminate adjacent the periphery of the metal disk 34 when the button 28 and stem 26 of the plunger is depressed inwardly to unarm the fuze. In this position, the long arms 18 of the striker lever are prevented from having any motion, and thus the fuze is rendered unarmed and safe. However, when the disk 34 is retracted on the outwardly ejected plunger as shown in Fig. 6, the long arms 18 of the striker levers are free to be actuated into movement by movement of weight 32 transmitted through links 31. The safety plunger assembly 7 may be fastened into recess 6 in the cylindrical head piece of metal. The head piece of the fuze is provided with thread 29 for engagement with a threaded hole in a munition. The head piece and base may be expeditiously made of die cast metal.

In free flight of a bomb or projectile carrying the all-ways fuze, the safety plunger is ejected or retracted by a spring, as described with reference to Fig. 4. Upon impact of the bomb or projectile on the target, the suspended weight 32 being free to move in any direction, continues to move in the general direction of flight while the munition is decelerated by impact. Regardless of the direction of the motion, resulting force components pull one or both of the long arms 18 of the striker levers towards the fuze center-line. This motion of one or both of the striker levers causes one or both the primers 9 to be fired, which in turn ignites the pressed powder core 11 of the delay element, then following the period of delay ignites the booster charge in cup 12. 75

The fuze may be made to operate instantaneously without delay by merely omitting the powder delay element or substituting therefore an instantaneous burning or detonating powder charge.

The types of primer, powder delay train, and booster charge which work well in the fuze are standard available materials. In tested fuzes which gave satisfactory results, new No. 4 primer caps manufactured for smokeless powder paper shot shells by Winchester Repeating Arms Co., New Haven, Conn., and covered by U. S. Army Specifications on Primer, new No. 4 were used. For the delay train, lead spitter fuses (consisting in a black powder mixture contained in a lead tube) $\frac{1}{8}$ inch length made by the Ensign-Bickford Co., Simsbury, Conn., and known as Type D were used. Army black powder, Grade A, No. 4 was used as a first fire charge in cellulose nitrate plastic cups (about 80% cellulose nitrate having approximately an 11% nitrogen content and plasticized by about 20% camphor), the cups having a wall thickness of about 0.01 inch, a depth of about $\frac{1}{16}$ inch, and made to fit snugly into a cylinder $\frac{1}{8}$ inch I. D. It will be understood, however, by those skilled in the art that variations may be made in the selection of the components, their ingredients and dimensions.

Fuze units made in accordance with this invention were subjected to extensive surveillance tests and met stringent requirements of standardization.

Some of the practical advantages of the fuze units are: (1) safety in assembling due to the independent restraining action of the torsion spring even when the safety plunger does not unarm the fuze; and (2) consistent cooperative action of the delay element and first fire charge with the primer in the combination unit.

It is to be noted that the fuze may be made of common materials with very small amount of machinery. The die casting of the fuze base, preferably of aluminum base alloy, greatly simplifies the construction, and very little tooling is needed for other portions of the fuze. Even though under some rigorous conditions, e. g., when a bomb has a high terminal velocity and impacts on concrete at an extremely low temperature on the order of minus 40° F., resulting in a fracturing of the die cast base, this failure does not prevent functioning of the firing mechanism since the outer case holds the fuze components intact.

Although the fuze embodiment illustrated in Fig. 1 functions most satisfactorily when such a fuze is positioned in a bomb body horizontally, so that its longitudinal axis is perpendicular to the longitudinal axis of the bomb, or so that the movement of the striker is in substantially the same direction as a flight of the bomb just prior to impact, the fuze may be positioned near the tail end as well as near the nose end of the bomb. On the other hand, the more responsive all-way fuze embodiment such as illustrated in Fig. 7, may be fixed in a bomb body or other type of munition in any position for satisfactory functioning, e. g., horizontally, vertically, or at any angle and in any part of the bomb or munition.

It is to be understood that although the invention has been described in detail with respect to preferred specific embodiments, that modifications come within the spirit and scope thereof.

I claim:

1. A combination fuze adapted for use in the

nose end of a tail ejection bomb, comprising a base having a generally cylindrical outline defined by circular disc portions forming the head and rear ends of the base, a primer charge well located intermediate said head and rear ends in the base, a pair of parallel lobes adjoining the rear end of the base, a pair of drilled holes aligned in said lobes to hold a hinge pin, a striker lever pivotally mounted at one end on a hinge pin passed through said drilled holes, a weighted portion at the other end of said lever, a firing pin in said striker lever at its free swinging end, a torsion spring coiled around said hinge pin with one end bearing against the striker lever to restrain its swinging movement, a vented passageway leading from the primer well in the base to the rear end of the base for holding a powder train delay element, a plastic cup for holding a first fire charge adjacent the rear end of the base, and a thin metal cylinder surrounding said plastic cup and fuze base up to the head end of the base.

2. A combination fuze as described in claim 1, in which the powder train delay element is in the

form of a lead spitter fuse, the plastic cup is a cellulose nitrate plastic, and the plastic cup contains a block powder first fire charge.

3. A combination fuze as described in claim 1, in which the fuze base is a die cast aluminum base alloy, and the cylinder surrounding the fuze base is made of a pressed steel.

LYLE M. COOPER.
